UNITED STATES PATENT OFFICE.

ALBERT D. JUDD, OF NEW HAVEN, CONNECTICUT.

DESIGN FOR HAT AND COAT HOOK.

Specification forming part of Design No. **6,694**, dated June 3, 1873; application filed May 20, 1873.

To all whom it may concern:

Be it known that I, ALBERT D. JUDD, of New Haven, in the State of Connecticut, have invented a Design for a Hat-Hook, of which the following is a specification:

The nature of the said design is fully represented in the accompanying perspective view.

The plate *a* is made with four rectangular projecting ornaments, in which are the screw-holes. The surface is recessed or countersunk, leaving the scroll and leaf ornaments *b*, as shown. The stem of the hook is fluted at *c* with leaf ornaments *d*, band *e*, and end ornaments *f* where the same joins to the bands *g*, forming the base of a bust *h*, and beneath *g* is the drop ornament *h'*. Between the base of the stem and the plate *a* there are bracing leaf ornaments branching backwardly from

the ring *k*, and the ends of the leaves *l* are curved so as to rest against the angles *n* of the plate *a*.

I claim as my invention—

1. The design of the shape and ornamentation of the plate *a*, as represented.
2. The design of the shape and ornamentation of the stem *c d e f*, as represented.
3. The design of the bust *h*, bands *g*, and drop *h'*, as represented.
4. The design of the bracing leaf ornaments *k l*, as represented.

Signed by me this 12th day of May, A. D. 1873.

A. D. JUDD.
